US0D1107013S

(12) **United States Design Patent** (10) Patent No.: **US D1,107,013 S**
(45) Date of Patent: ** Dec. 23, 2025

(54) **COMPUTER CASE**

(71) Applicant: **x-ion GmbH**, Hamburg (DE)

(72) Inventor: **Martin Bosner**, Hamburg (DE)

(73) Assignee: **x-ion GmbH**, Hamburg (DE)

(**) Term: **15 Years**

(21) Appl. No.: **35/522,432**

(22) Filed: **Jul. 5, 2024**

(80) **Hague Agreement Data**

Int. Filing Date: **Jul. 5, 2024**

Int. Reg. No.: **DM/240182**

Int. Reg. Date: **Jul. 5, 2024**

Int. Reg. Pub. Date: **Sep. 27, 2024**

(51) **LOC (15) Cl.** **14-02**

(52) **U.S. Cl.**

USPC **D14/314**

(58) **Field of Classification Search**

(57) **CLAIM**

The ornamental design for a computer case, as shown and described.

DESCRIPTION

1.1 is an elevated left-side perspective view of a computer case;

1.2 is an elevated right-side perspective view thereof;

1.3 is front view thereof;

1.4 is a back view thereof;

1.5 is a right-side view thereof;

1.6 is a left-side view thereof;

1.7 is a top view thereof; and

1.8 is a bottom view thereof.

The portions in the drawings shown in the broken lines form no part of the claimed design.

1 Claim, 8 Drawing Sheets
